2,289,404

ELECTRIC SIGN

Elmer L. Ballew, Saginaw, Mich.

Application January 17, 1940, Serial No. 314,213

5 Claims. (Cl. 240—10.1)

This invention relates to an electric sign.

An object of the invention is to provide a novel electric sign by means of which the illusion of moving spots or areas of light may be created in a novel and distinct manner.

Another object of the invention is to provide a novel electric sign which is constructed and arranged in such a manner that spots or areas of light will appear to be moved along the axis of a spiral shaped rotating member when the device is in operation thereby creating the illusion of a continual moving spiral band or series of light spots or areas.

Another object of the invention is to provide an electric sign comprising an elongated stationary luminous tube and an opaque spiral member rotatably mounted thereon whereby when the spiral member is rotated a band of light will be caused to move spirally along the axis of the stationary luminous tube.

Another object of the invention is to provide a display device or sign which is particularly adapted for use in conjunction with outdoor advertising signs, window signs, store fronts, signals, highway and railroad crossings, and the like.

Other objects will appear hereinafter.

The invention consists in the novel combination and arrangement of parts to be hereinafter described and claimed.

The invention will be best understood by reference to the accompanying drawing showing the preferred form of construction, and in which:

Fig. 1 is a perspective view of a preferred form of the new electric sign; and

Fig. 2 is a fragmentary perspective view of a modification of the invention.

A preferred form of the invention is shown in Fig. 1 of the drawing wherein 4 indicates a so-called luminous tube which is shown as being mounted upon suitable supporting brackets 2 which may be attached to any suitable support by means of fastening elements 3. The luminous tube 4 has end portions which are received in housings 6 and these end portions are provided with terminals 5 to which are attached current-conducting wires 8 which, in turn, are attached to the housings 6 by means of suitable clamping nuts 7.

Rotatably mounted upon the luminous tube 4 is a spiral member 1 which is made of suitable opaque materials such as metal, this spiral member 1 being adapted to be driven by any suitable operating mechanism such as that which is shown in Fig. 1 and which comprises a motor

arranged in the housing 9 and operating a pulley and belt mechanism 10—11—12.

In the use of that form of the invention which is illustrated in Fig. 1 the spiral member 1 is rotated upon the luminous tube 4 by means of the motor mechanism 10—11—12, and when thus rotated the illusion of a spirally moving band of light is created as portions of the luminous tube 4 are successively exposed to view by the spaces between adjacent convolutions of the spiral member 1.

It will be noted that the convolutions of spiral member 1 gradually decrease in size from one end to the other, and in this form of the invention, when the spiral member 1 is rotated the sizes of the light spots or spirally moving bands of light successively exposed to view will be varied by reason of the gradually changing size of the spaces between successive convolutions of the spiral member 1.

It will be seen, therefore, that the device shown in Fig. 1 may be used as an advertising or display device for the purpose of attracting attention of passersby, and as such may be used in various places such, for example, as drug stores, gasoline filling stations and the like.

A modified form of the invention is shown in Fig. 2, and this form of the invention differs from that which is shown in Fig. 1, in that the stationary luminous tube 4, instead of being straight, as is the luminous tube 4 which is illustrated in Fig. 1, has a curvilinear or arc shape, and the spiral member 1 which is rotatably mounted thereon, is of a corresponding shape and may be driven by a suitable operating mechanism such as that shown in Fig. 1.

Hence, it will be seen that my invention provides novel and attractive means for catching the eye of a passerby and is well adapted for any one of a number of purposes such as, for example, to be used in a warning signal or as part of an advertising display.

While I have illustrated and described the preferred forms of construction for carrying my invention into effect, these are capable of variation and modification, without departing from the spirit of the invention. I, therefore, do not wish to be limited to the precise details of construction set forth, but desire to avail myself of such variations and modifications as come within the scope of the appended claims.

I claim:

1. A display device comprising an elongated luminous tube, a spiral member rotatably mounted upon the said luminous tube and having spiral

convolutions varying gradually in length axially thereof, and means for rotating the said spiral member relative to and around the said luminous tube.

2. A display device comprising a stationary elongated luminous tube, a spiral member rotatably mounted upon the said luminous tube and having spiral convolutions varying gradually in length axially thereof, and means for rotating the said spiral member relative to and around the said luminous tube.

3. A display device comprising a curvilinear elongated luminous tube, a curvilinear spiral member rotatably mounted upon the said luminous tube and having spiral convolutions varying gradually in length axially thereof, and means for rotating the spiral member relative to and around the said luminous tube.

4. A display device comprising a curvilinear stationary elongated luminous tube, a curvilinear spiral member rotatably mounted upon the said luminous tube and having spiral convolutions varying gradually in length axially thereof, and means for rotating the spiral member relative to and around the said luminous tube.

5. A display device comprising a light source, a substantially spiral-shaped member mounted for rotatable movement about the said light source and having substantially spiral convolutions varying gradually in length axially thereof, and means for rotating the said spiral member relative to and around the said light source.
